UNITED STATES PATENT OFFICE.

WESTERN UNDERWOOD, OF LOS ANGELES, CALIFORNIA, ASSIGNOR OF ONE-HALF TO
H. H. WALKER, OF LOS ANGELES, CALIFORNIA.

DESIGN FOR A LANTERN FOR LIGHTING POSTS.

Application filed September 12, 1928. Serial No. 28,119. Term of patent 7 years.

To all whom it may concern:

Be it known that I, WESTERN UNDERWOOD, a citizen of the United States, residing at Los Angeles, in the county of Los Angeles and State of California, have invented a new, original, and ornamental Design for a Lantern for Lighting Posts, of which the following is a specification, reference being had to the accompanying drawing, forming a part thereof.

I claim:

The ornamental design for a lantern for lighting posts, as shown.

WESTERN UNDERWOOD.
